(57) **CLAIM**

The ornamental design for a container bracket, as shown and described.

DESCRIPTION

FIG. 1 is a perspective view of a container bracket in accordance with our design, shown in environmental use; FIG. 2 is a partial perspective view thereof, shown in environmental use;

FIG. 3 is a right side view thereof;

FIG. 4 is a left side view thereof;

FIG. 5 is a top plan view thereof;

FIG. 6 is a bottom plan view thereof;

FIG. 7 is a front view thereof; and,

FIG. 8 is a back view thereof.

The broken lines in FIGS. 1 and 2 illustrate environmental matter that forms no part of the claimed design.
